Specification of Letters Patent. Patented Feb. 13, 1912.

Application filed June 27, 1910. Serial No. 569,020.

To all whom it may concern:

Be it known that I, IRA H. SPENCER, a citizen of the United States, and a resident of Hartford, in the county of Hartford and 5 State of Connecticut, have invented a new and Improved Separator, of which the following is a specification.

My invention relates to the class of devices for separating dust and heavier matter 10 from a volume of air, and the object of the invention among others is to provide a device of this class compact in construction and extremely durable and efficient in operation.

15 One form of device embodying my invention and in the use of which the objects sought may be attained is illustrated in the accompanying drawings, in which—

Figure 1 is a view in elevation, partly in 20 section, of a device embodying my invention. Fig. 2 is a top plan view of the same. Fig. 3 is a detail view illustrating the manner of securing the dirt receiver.

While my invention is applicable to various forms of devices for separating dust and heavier matter from a volume of air, as 25 it finds ready adaptation in connection with apparatus designed for suction cleaning, I have selected such a device for the purpose 30 of disclosure of my invention herein.

In the accompanying drawings the numeral 5 indicates a shell, constructed of any suitable material and of any desired form, as shown herein this being made up of sections 6 of ring form closely fitting one upon the other. A base 7 supports the shell and 35 is provided with an outlet opening, shown herein as embodied in a tubular projection 8. The base also has a cleanout opening 40 closed by a removable plate 9.

In devices of this character in which more or less dust and dirt are mixed with the air passing through the shell it is important that all bearings shall be so constructed as 45 not to be affected by any dust that may gain access thereto. The device herein illustrated and described and embodying my invention contains such features of construction, a motor 10 of any suitable type being mounted 50 on the shell that is closed at its top by a cap 11 having standards 12 rising therefrom to support the motor. This construction of the standards provides spacious openings to a bearing 13 of the motor, in which bearing 55 the shaft 14 is supported, which shaft is rig-

idly connected with or forms an extension from the armature shaft of the motor. The shaft 14 extends downward within the shell 5 and supports a set of fans by means of which a current of air is caused to travel 60 through the shell. The lower end of the shaft is, in normal operation, unsupported, but in order to guard against excessive lateral movement during critical speeds which are liable to momentarily occur for various 65 reasons I provide a guard bearing 16 at the bottom of the shaft, this being composed of a projection rising from the chamber in the base 7 in which projection a recess 17 of a size somewhat larger than the diameter of 70 the shaft, is formed so that when the shaft is running naturally and truly there will be no contact between it and the bearing, but whenever lateral movement may momentarily occur for any reason the bearing will 75 support the shaft and guard against excessive movement in this direction. The recess may be lined with any suitable antifriction material 18 which will receive the shaft whenever undue lateral movement occurs. 80 A dust cap 19 is secured to the shaft and has a flange 20 extending downward about the outer surface of the projection or bearing 16, the distance between opposite sides of the inner wall of this flange being slightly 85 greater than the distance across the projection 16, so that there will be no contact of the parts in normal operation, but dust will be prevented from entering within the recess 17. 90

The cap 11 includes a crown 21 overlying the interior of the shell and having an inlet opening 22. The cap also includes an overhanging dust receptacle support 23 preferably integrally formed with the cap and of circular shape, with an opening 24 therein. A ridge 25 is integrally formed with the cap 11 and plate or dust receptacle support 23, this ridge being of suitable shape to contain a communicating passage 26, the ridge being of a length to extend over the openings 22 and 24 and the communicating passage 26 extending between said openings. A boss 40 is formed on top of the ridge 25 and the shaft 14 extends through this boss. A gland 41 is fitted within the boss providing a stuffing box construction through which the shaft extends. 100

The support 23 has a depending wall 28 within which is formed an inlet opening 29. 110

located in a tubular projection 30 to which a hose or like conveying member may be secured. A flange 31 is located at the lower edge of the wall 28 and has a recess in its under edge for the reception of a packing 32 against which the upper edge of a receptacle 27 is forced when secured in place. This receptacle may be removably secured to the depending wall 28 in any suitable manner, a preferred form of fastening including lips 33 extending from opposite sides of the wall 28, each lip having an opening through which a bolt 34 extends, each bolt being hinged between the forked ends 35 of a clamp lever 36. A nut 37 or other enlargement at the end of each bolt 34 underlies an ear 38 in which a slot is formed to receive the bolt, the slots in the ears on each side opening in the opposite direction from that on the opposite side, so that as the receptacle 27 is turned each bolt will pass into its slot. The lever being then moved downward action of the cams 39 will draw the receptacle tightly to its seat, the cam being so located that it will pass beyond the line drawn through the pivot of the lever and the point of attachment of the bolt, so that the strain will hold the lever in the position shown in Fig. 3.

30 I do not limit my invention and the scope of the following claims to the foregoing illustration and description of the preferred form of the invention in which it has been embodied, as these may be departed from to 35 a greater or less extent without avoiding the invention.

I claim—

1. In combination, a shell, a cap fitting the top of said shell and having an extension projecting beyond the side of the shell upon one side, a receptacle secured to the underside of said extension and depending therefrom and wholly supported thereby, said receptacle having an inlet, a communicating passage extending through said cap and extension to the interior of the shell, and means for forcing a current of air through the shell.
2. In combination, a shell, a cap fitting the top of said shell and having an extension at one side projecting beyond the side of the shell, a ridge located upon the upper surface of said cap and extension and having a communicating passage to the interior of the shell and underside of said extension, a receptacle secured to the under surface of the extension and depending therefrom and wholly supported thereby, said receptacle having an inlet opening, and means for creating a current of air in the shell.
3. In combination, a shell, a cap fitting

said shell and having an extension at one side edge projecting beyond the side of the shell and with a depending wall therefrom, said wall having an inlet opening, a receptacle secured to and wholly supported by said depending wall, a communicating passage extending from the under surface of the cap to the under surface of the extension, and means for forcing a current of air through the shell.

4. In combination, a shell, a cap fitting said shell and having an integral extension at one side edge overhanging the side of the shell and with a depending wall, a receptacle removably secured to said depending wall and wholly supported thereby, means for holding the receptacle in place, said wall having an inlet opening, a flange projecting downward from the under surface of said projecting part providing an annular chamber between said flange and said depending wall and with an opening through the cap within said flange, a communicating passage between said opening and the interior of the shell, and means for creating a current of air in the shell.

5. In combination, a shell composed of rings superimposed, the upper ring constituting a cap to close the top of the shell and having an extension at one side projecting beyond the side of the shell, and with a ridge extending across the upper surface of said cap, a receptacle removably secured to the under side of said cap at one side of the shell and wholly supported by said cap, and with a communicating passage between the underside of the projecting part and the under surface of the cap overlying the shell, and means for creating a current of air in the shell.

6. In combination, a shell, a cap fitting said shell and having an extension at one side edge with a depending wall, said wall having an inlet opening, a receptacle secured to and wholly supported by said depending wall, a ridge extending across the upper surface of said cap and extension, said ridge having a communicating passage between the under surface of the cap and the under surface of the extension, a shaft projecting through said ridge and through said passage into the interior of the shell, a stuffing box formed on the outer surface of said ridge, and means upon said shaft for creating flow of a current of fluid through the shell.

IRA H. SPENCER.
